Primary Examiner — Melanie H Tung(74) *Attorney, Agent, or Firm* — Sterne, Kessler, Goldstein & Fox PLLC(57) **CLAIM**

The ornamental design for a graphical user interface for a display screen or a portion thereof, as shown and described.

DESCRIPTION

FIG. 1 is a front view of a graphical user interface for a display screen or portion thereof showing my new design; and, FIG. 2 is a front view of a second embodiment thereof. The broken line showing of the display screen in both views is not part of the claimed design.
